UNITED STATES PATENT OFFICE

2,489,177

WATER INJECTOR

Jesse L. French, Pond Creek, Okla.

Application July 23, 1946, Serial No. 685,753

4 Claims. (Cl. 103—54)

1

This invention relates to an automatic water injector, or other liquids. The primary object of this invention is to provide a practical but cheap way of supercharging an internal combustion engine with water or other liquids, to give them the performance of Diesel engine power without losing any of its higher speed, as water or other liquids are injected into said cylinder after combustion has taken place, therefore, will not slow up combustion in said cylinder of engine.

It is also an object of this invention to provide an automatic injector of this kind which operates from combustion in cylinder to deliver the right amount of water or other liquids to properly supercharge said cylinder after combustion of gases has taken place.

This invention has a further object which is to cause oil to adhere to piston rings, cylinder walls and valves by means of dampness in cylinder, thereby lowering temperature and friction.

A more particular object of this invention is to provide an injector including a valve normally closing the flow of liquids into combustion cylinder and which valve is moved into open position by pressure of the explosion within the combustion chamber.

It is a further object of this invention to lower cost of operation of internal combustion engines, as the amount of power developed by injector supercharger will lower amount of gas fuel used.

It is a still further object of this invention to have an injector that will not interfere with normal operation of said combustion engine, when said injector has no liquids. There are just two moving parts to said injector.

It is an additional object of the invention to design two different check valves for said injector, such as the valve-shaped piston with rings for heavy duty engines and the ball-check for light-weight engines.

The invention consists in the details of construction and in the combination and arrangement of the several parts of my improved water injector whereby certain important advantages are attained, as will be hereinafter more fully set forth.

In order that my invention may be better understood, I will now proceed to describe the same with reference to the accompanying drawing, wherein is illustrated a view partly in section and partly in elevation of an injector constructed in accordance with an embodiment of the invention.

In the embodiment of the invention as illustrated in the accompanying drawings, C denotes

2

a cylinder of an internal combustion engine in which operates a reciprocating piston P. As the means for admitting the explosive charge within the combustion chamber 1 of the cylinder C forms no part of the present invention, a detailed description and illustration thereof are believed to be unnecessary.

The head 2 of the cylinder C at its axial center is provided with an opening 3 into which threads an end portion of an elongated valve cylinder or sleeve 4 of desired dimensions. The inner end portion of the wall of the cylinder or sleeve 4 is increased in thickness, as at 5, to produce an internal valve seat 6 with which engages a valve member M.

The valve member M, as herein disclosed, comprises a short tubular member 7 snugly fitting within the cylinder or sleeve 4 and carrying surrounding piston rings 8 to assure against leakage between the member 7 and the wall of the cylinder or sleeve 4.

The outer end of the tubular member 7 is closed by the head 9, herein disclosed as having an outer convex face, and the marginal portion of the head 9 is formed to provide an internal surrounding shoulder 10 with which contacts an expansible member 11 of requisite tension and herein disclosed as a coil spring. The outer end of this member or spring 11 has contact with the inner face of the plug 12 which threads within the outer extremity of the cylinder or sleeve 4 and provides means whereby the tension of the member or spring 11 may be regulated as the requirements of practice may necessitate.

The cylinder or sleeve 4 has an inner portion outwardly enlarged, as at 14, extending a desired distance along the cylinder or sleeve 4 and disposed through this enlargement 14 is a passageway 15, the outer end of which passageway 15 is in communication with the interior of the cylinder or sleeve 4 through a relatively large port 16 while the opposite or inner end portion of the passageway 15 has in communication therewith the restricted ports 17 disposed through the wall of the cylinder or sleeve 4 and spaced lengthwise thereof.

Coacting with each of these restricted ports 17 is a needle valve 18 threading through the wall of the enlarged portion 14. These needle valves 18 provide means whereby flow through the restricted ports 17 may be regulated.

It is to be particularly noted that the lowermost port 17 meets with the cylinder or sleeve 4 at a point below the rings 8 when the valve member M is seated and also above but in close prox-

inity to the valve seat 6. This particular location of the lowermost port 17 is of importance for the reason that when the valve member M is forced upward by the force of the explosion within the cylinder C, the pressure equalizes if water is not released in the first few degrees of the upward travel of the valve member. The valve seat 6 also serves to provide a water seal when the valve member M is seated thereon.

The cylinder or sleeve 4, preferably at a point diametrically opposed to the port 16, is provided with a port 19 in which is fitted an outstanding nozzle 20 carried by an end of a casing 21. The outer end portion of this casing 21 is provided with an internal valve seat 22 with which coacts the inwardly opening spring-pressed check valve 23. The casing 21 has suitably connected thereto a pipe line 24 leading from a suitable source of water supply.

In practice, the force of the explosion within the combustion chamber 1 of the cylinder C will result in an inward or opening movement of the valve member M, allowing a jet of water to enter the chamber 1 and thereby increase the effectiveness of the charge and which is particularly desirable in connection with heavy duty engines, such as tractors, etc.

It is to be stated that the member or spring 11 initially has its tension adjusted by proper manipulation of the plug 12, so that the valve member will not leave its seat 6 during a low throttle or the idle operation of the engine but, as the force becomes greater, the valve member M will be lifted, thus allowing an increased amount of water to be discharged within the combustion chamber 1.

It is believed to be obvious that the valve member M will automatically reseat itself.

From the foregoing description it is thought to be obvious that a water injector constructed in accordance with my invention is particularly well adapted for use by reason of the convenience and facility with which it may be assembled and operated.

I claim:

1. An injector for forcing liquid under pressure into the cylinder of an internal combustion engine above the piston by the action of combustion pressure in the cylinder, comprising a relatively long housing having an open end opening into the said combustion chamber and formed adjacent to the said open end to pro-

vide an internal valve seat, a valve member slidable in the housing, yieldable means for urging the valve member to said seat, means forming a bypass passage around the valve member and opening at one end into the housing across the valve seat and opening at its other end into the housing behind the valve member, said valve member operating to close the said one end of the bypass and also the said open end of the housing when the valve member is on its seat, means for introducing liquid into the housing behind the valve member, and means for preventing reverse flow of liquid through the said introducing means.

2. An injector of the character stated in claim 1 in which the opposite end of the housing is closed by an inserted plug, said plug being retained by screw threads engaging corresponding threads in the wall of the housing, and said yieldable means being in the form of a spring interposed between the inserted plug and the valve member, said inserted plug facilitating the increasing or decreasing of the spring pressure against the valve member.

3. An injector of the character stated in claim 1 wherein the opening of the said one end of the bypass passage into the housing is in the form of a needle valve seat, and a needle valve adjustably supported across the bypass passage and having its inner end disposed for engagement with the last mentioned valve seat.

4. An injector of the character stated in claim 1, with a further opening from the bypass passage into the housing at a point spaced longitudinally of the housing from the said one end of the bypass passage, said further opening also being closed by the valve member at all times except when the valve member is open to its extreme position, and control valves for the said opening at the one end of the bypass passage and the said further opening.
